UNITED STATES PATENT OFFICE

JAMES L. GRISSINGER, OF MARION, OHIO, ASSIGNOR TO THE MARION STEEL BODY COMPANY, OF MARION, OHIO, A CORPORATION OF OHIO

DESIGN FOR A BURIAL VAULT

Application filed February 5, 1932. Serial No. 42,745. Term of patent 7 years.

To all whom it may concern:

Be it known that I, JAMES L. GRISSINGER, a citizen of the United States, residing at Marion in the county of Marion and State of Ohio, have invented a new, original, and ornamental Design for a Burial Vault, of which the following is a specification, reference being had to the accompanying draw-

ing, forming part thereof, wherein Fig. 1 is a perspective view and Fig. 2 is an end elevation of a burial vault.

I claim:

The ornamental design for a burial vault, substantially as shown.

JAMES L. GRISSINGER.
